UNITED STATES PATENT OFFICE.

LEWIS M. MCPHERSON AND MARY J. F. GRUNDY, OF CHICAGO, ILLINOIS.

ANTICHAFING AND MENSTRUAL GARMENT.

1,031,861.

Specification of Letters Patent.

Patented July 9, 1912.

Application filed August 7, 1911. Serial No. 642,868.

To all whom it may concern:

Be it known that we, LEWIS M. MCPHERSON and MARY J. F. GRUNDY, citizens of the United States, residing at Chicago, in the county of Cook and State of Illinois, have invented new and useful Improvements in Antichafing and Menstrual Garments, of which the following is a full, clear, and exact description.

Our invention relates to garments worn by women to prevent chafing of the limbs in the crotch or inner part of thighs, and to prevent the soiling of the clothing during the menstrual periods.

The object of our invention is to provide a simple garment that can be worn without discomfort and is particularly adapted for use by stout women.

It is also an object to construct this garment so that a peculiarly shaped napkin used in connection therewith can be readily attached thereto and worn with a great deal more comfort without danger of the shields of the garment or the clothing of the wearer being stained or soiled, and a further object of our invention is to provide a simply constructed but effective napkin that can be used in conjunction with the garment and prevent the percolations of the menstrual flow or hemorrhage through the napkin to the shields or other parts of the garment or clothing and will retain and hold the discharge.

These objects we accomplish by the means and in the manner hereinafter fully described and as more particularly pointed out in the claim.

In the drawings:—Figure 1 is a front view of our invention. Fig. 2 is a central vertical section therethrough. Fig. 3 is a transverse section through one of the legs of the garment. Fig. 4 is a plan view of the napkin constituting part of said invention. Fig. 5 is a transverse section through the central portion of said napkin.

Referring to the drawings, A represents short drawers or trunks, that are preferably made of porous fabric and have legs a, a. On the inner side of each leg we provide suitably shaped shields B, B, to the inside of the fabric. The top of said shields, preferably, touch the crotch of the legs and extend both toward the front and the rear thereof, and these shields are preferably of the usual shield-shape (that is, more or less triangular in shape), and are secured on

their sides to the ends of elastic bands C that surround the legs at the thighs. These bands are, preferably, secured to the inside of the fabric of which the garment is composed, and have a tendency to draw the upper edges of the shields away from the crotch and hold them tight to prevent their movement on the limbs of the wearer. The lower angles of the shields extend to the lower edges of the legs, and these lower edges c have an elastic b, b, inclosed in the hems with which the edges are finished.

We prefer to provide the outer side of the fabric of the garment, opposite and in front of the bands C, with straps D, D', and one of the lapping ends of one of which is provided with a buckle d, of any of the conventional designs, so that by tightening said straps a better adjustment of the bands at the thighs of the wearer can be obtained to adapt the garment to different sized limbs. We do not desire to be confined to the conjoint use of said bands C and straps D, D', as it is obvious that either of them could be used without the other.

The waist-band E of the drawers is, preferably, made deeper in front and in the rear than at the sides; in other words, has its lower edge at these points extended downward a suitable distance toward the crotch, and two short straps e, e, secured thereto, which latter, in turn have a more or less semi-circular flap F secured to their pendent ends. The waist-band and this flap are preferably made of heavier material or of several thicknesses of material or of rubber webbing in order to support the end of the napkin G, which is secured thereto by means of buttons that engage the button-holes f, therein, and at the sides is preferably composed of elastic webbing K, so as to surround the abdomen comparatively tightly above the hips and insure the napkin being held snugly in the crotch.

The napkin to which reference has just been made comprises a longitudinally elongated strip of sufficient length to extend through the crotch of the wearer from one flap F. This strip is adapted to be folded over laterally to make it of a width of about one-half of the original width of the pattern and the lapping edges of the ends of these folded over portions are, preferably, sewed together, so as to leave the edges of the central portion of its longitudinal edges disconnected for a length about the equiva-

lent of one-third or one-half the total length of the strip to form a pocket. A rectangular pad *R*, of rubber or other waterproof material is secured to the under fold *g* of 5 this pocket preferably in such manner that it can be removed therefrom when desired. Projecting from the free longitudinal edge of the under fold *g* of the pocket adjacent to said pad *R*, is a laterally extending flap 10 *h*, preferably of the same material as said strip, which, in use, is adapted to be folded over several times and then tucked into said pocket over the rubber pad *R*. This flap *h*, when thus folded and tucked into said 15 pocket forms an absorbent for the menstrual flow or hemorrhage, and when the napkin is being worn it is secured in place in the crotch of the limbs of the wearer in such manner that the waterproof pad will be 20 undermost, and the absorbent flap uppermost, and the menstrual flow will be retained by and prevented from percolating through the material of the napkin by the pad. The sewed together ends of the folds 25 of the strip are, preferably, each provided with a button *k*, and these buttons, when

the napkin is being worn, are adapted to engage in one of a series of button-holes *f* in pads *E* of the waist-band according to the dimensions of the wearer. If desired, the 50 flap *h*, can be dispensed with, and absorbent cotton introduced in the central pocket, or both be used. We prefer to use the flap, however.

What we claim as new is:

A garment of the kind specified comprising a pair of drawers, shields attached to the inner sides of the legs of the same next the crotch, elastic bands attached to the fabric of the legs of the garment on the inside, 40 whose ends are attached to the shields, overlapping straps secured to said fabric outside of said legs opposite and in the same plane as said bands, and an elastic band hemmed into the lower edges of said legs. 45

In witness whereof we have hereunto set our hands this 31st day of July, 1911.

LEWIS M. McPHERSON.
MARY J. F. GRUNDY.
